Patented Apr. 2, 1968

210,684

MOLDED LANTERN

Nolan K. Rhoades, Stoughton, and Ralph T. Jacobsen,
Beloit, Wis., assignors to ESB Incorporated, Philadelphia, Pa., a corporation of Delaware

Filed Sept. 22, 1967, Ser. No. 8,690

Term of patent 14 years

(Cl. D48—24)

FIG. 1

FIG. 2

FIG. 3

FIG. 4

FIG. 5

FIG. 6

FIG. 1 is a perspective view of the portable molded lantern showing our new design;

FIG. 2 is an elevational view of the front thereof;

FIG. 3 is an elevational view of the rear thereof;

FIG. 4 is an elevational view of one side thereof, the other side not shown being identical;

FIG. 5 is a plan view looking downwardly at the top thereof; and

FIG. 6 is a plan view looking upwardly at the bottom of the portable molded lantern.

We claim:

The ornamental design for a molded lantern, as shown and described.
